UNITED STATES PATENT OFFICE.

HAMILTON H. McNUTT, OF BEGGS, OKLAHOMA.

RAIL JOINT.

Application filed March 7, 1927. Serial No. 173,566.

The present invention relates to improvements in rail joints and has for its primary object to provide a joint structure which will durably secure the meeting ends of 5 rails.

A further object of the invention is the provision of a rail joint structure embodying means for firmly securing the same upon the rail ties.

10 Another object of the invention is the provision of a rail joint embodying a pair of complementary plates formed with reinforcing connecting brackets adapted to maintain the rails in longitudinal alignment.

15 Still another object of the invention is the provision of a rail joint of the above character which is durable in construction and which can be conveniently connected in association with the rails and which will be efficient in use.

20 Other objects and advantages of the invention will become apparent as the description progresses.

25 In the accompanying drawing forming a part of this specification and in which like reference characters are employed to designate corresponding parts throughout the same:

30 Figure 1 is a side elevational view of my improved rail joint construction shown operatively connected with the meeting ends of railroad rails.

Figure 2 is a top plan view of the same.

35 Figure 3 is a transverse sectional view taken on the line 3—3 of Figure 1, and

Figure 4 is a similar view taken on the line 4—4 of Figure 1.

40 Referring to the drawing wherein for the purpose of illustration is shown the preferred embodiment of my invention, the numeral 10 generally designates the end portions of a pair of rail sections, the meeting ends being formed to provide transverse 45 abutting connections. The rails 10 embody vertical web portions 11, base flanges 12 and rail heads 13, and are of standard construction.

50 The primary feature of the present invention is to provide means for securely connecting the abutting ends of the rail sections to prevent longitudinal or lateral displacement. With this in mind, my improved rail joint embodies a pair of complementary sections 14, each section comprising 55 a longitudinal rectangular shaped side plate

15 adapted to be arranged in vertical position against the rail web 11 and formed with a bottom flange 16 projecting outwardly at an angular inclination and adapted to rest 60 upon the upper face of the rail flange. The side plates 15 are of arcuate cross sectional design and their upper and lower edges bear against the rail web as at 17 and maintain the central portion of the side plates 15 65 separated therefrom. Each of the side plates 15 is formed with a plurality, preferably six, of transversely aligned openings, also aligning with openings formed in the meeting ends of the rail sections 10 and 70 through which bolts 18 are positioned.

Formed on each of the plates 15 and spaced evenly from the ends thereof are three reinforcing brackets 19 embodying angular shaped bars formed integral with the 75 plate arranged in vertical positions and provided with transversely extending sleeves 20 formed on the lower end of the bracket and spaced below the plate flanges 16. The sleeves 20 are formed to be tightly 80 fitted against the under side of the rail flange 12, the said sleeves being formed with longitudinal bores arranged in transverse alignment through which are extended bolts 85 21 to provide an auxiliary connection for the plates.

Formed in spaced positions on the flanges 16 of the side plates are a plurality, in the present instance four, inverted U-shaped pockets 22 arranged in laterally opposed positions on the plates. These pockets are engageable with clamping members embodying a transversely extending base plate 23 adapted to extend below the rail flange having an angular flange engaging lug 24 90 95 formed on one end and provided with an extension 25. Detachably engageable with the opposite end of the base plate 23 is a rail bracket 26 comprising an angular lug 27 and a connecting plate 28 having an aperture adapted to align with a similar aperture formed in the end of the base plate. The angular lugs 24 and 27 are arranged to be tightly fitted over the outer edges of the flanges 16 and are slidably fitted in the 100 105 pockets 22 formed thereon. The plates 23 and 28 are provided with suitable apertures to receive fastening members such as the usual spikes which may be driven into the rail ties in the usual manner.

110 From the foregoing description and the drawing, it will be readily noted that the

present invention presents an exceedingly durable and efficient joint structure adapted to securely fasten the meeting ends of the rail sections so as to eliminate the danger of separation or displacement. The complementary joint sections are designed so as to be quickly and conveniently secured in association with the meeting ends of the rails and formed to permit rapid disconnection when necessary.

It is to be understood that the form of my invention herewith shown and described is to be taken as the preferred example of the same and that various changes as to the size, shape and arrangement of parts may be resorted to without departing from the spirit of the invention or the scope of the subjoined claims.

As will be readily seen from Figures 1 and 4 of the drawing, the clamp members 23 are adapted to be securely fastened to the cross ties of the railway track thus insuring the positive positioning of the structure.

Having thus described my invention, I claim:

1. A rail joint comprising a pair of complementary plates, a pair of angular brackets formed on the plates having transverse sleeves formed thereon adapted to extend below the rail flanges, the said sleeves being adapted to receive securing bolts, and pockets formed on the complementary joint sections engageable with clamping members.

2. A rail joint comprising a pair of complementary sections each section embodying a plate formed with a flange at its lower edge adapted to be positioned against the web of the rail, angular brackets formed on each of the section plates, transversely directed sleeves formed on the lower ends of the brackets adapted to engage the lower surface of the rail flange, and means to provide inverted U-shaped pockets on the flanges of the plates for connection with clamping members.

3. A rail joint comprising a pair of complementary fastening sections, each section including a longitudinal plate adapted to be positioned against the sides of the rail webs, outwardly directed flanges formed on the lower edges of the plates adapted to rest upon the flanges of the rails, the said plates being provided with a longitudinally extending series of apertures for alignment with openings in the rail web for the extension of bolts therethrough, angular brackets formed on the outer sides of the plates and flanges and formed with transversely aligned sleeves at the lower ends arranged for the projection of securing bolts there-

through, and means to provide a plurality of transversely opposed inverted U-shaped pockets formed on the section flanges adapted to engage clamping members.

4. A rail joint comprising a pair of complementary fastening sections, each section including a longitudinal plate, the said plates being positioned against the webs of the rails, flanges formed on the lower edges of the plates adapted to rest upon the rail flanges, auxiliary fastening brackets formed in opposed positions on the plates and flanges and provided with transversely aligned sleeves at the lower ends, the said plates being adapted to be connected by transversely extending bolts passed through said sleeves, means to provide a plurality of pockets on the flanges at opposed positions, and clamping members detachably engageable with the section plates and pockets formed thereon for connection with rail ties.

5. A rail joint connection of the character described, comprising a pair of relatively long plates designed to be positioned against the opposite faces of a rail web, a flange formed along the lower edge of each of said plates to rest upon the upper surface of the adjacent portion of the rail base, a clamping member designed to extend transversely of the under face of the track rail, means carried upon said member adjacent one end thereof for engagement over an overlying plate flange, removable means engageable with the clamping member adjacent the opposite end thereof for engagement over the flange of the other of said plates, and means for securing said clamping member to a rail supporting cross tie.

6. A rail joint connection of the character described, comprising a pair of relatively long plates designed to be positioned against the opposite faces of a rail web, a flange formed along the lower edge of each of said plates to rest upon the upper surface of the adjacent portion of the rail base, a clamping member designed to extend transversely of the under face of the track rail, means carried upon said member adjacent one end thereof for engagement over an overlying plate flange, removable means engageable with the clamping member adjacent the opposite end thereof for engagement over the flange of the other of said plates, means for securing said clamping member to a rail supporting cross tie, and means to provide a receiving pocket upon the upper face of each of said plate flanges for the reception of the flange engaging members carried by the clamping member.

In testimony whereof I affix my signature.

HAMILTON H. McNUTT.
